KEYHOLDER

Eldridge R. Fenimore Johnson, Moorestown, N. J.,
assignor to Mechanical Improvements Corporation,
Camden, N. J., a corporation of New Jersey

Application May 26, 1933, Serial No. 673,075

1 Claim. (Cl. 150—40)

This invention relates to a key holder, and more particularly to a key holder provided with a wrapper in which the keys may be normally enclosed.

5 In order to prevent chafing of the pocket or other receptacle in which a group of keys is carried, a wrapper is desirable therefor, and it is furthermore desirable that such wrapper be not only readily opened and closed but also that it
10 not interfere with ready and convenient manipulation and separation of the keys when the wrapper is opened up.

Letters Patent No. 1,898,202 of Henry H. Murray, granted February 21, 1933, for Key 15 holders, disclose a simple and compact holder for keys which enables them to be assembled in flat-wise engagement and alignment, and individually rotated into and out of the group for use, this construction having as an important advantage
20 that the keys are readily separable and manipulated by the use of one hand. Experience has demonstrated that if a flexible wrapper large enough to envelop the keys be attached to one end of such a key holder, at a point approxi-
25 mately midway of one side of the wrapper, so that the wrapper may be folded about the grouped keys and retained in position as by a snap, a simple and inexpensive container for the grouped keys is provided which produces a compact
30 package and at the same time eliminates chafing of the pocket or other receptacle in which it is carried.

Experience has further demonstrated, however, that a wrapper of the aforesaid character 35 tends to wrinkle and bunch up, and interfere with the separation and use of the keys, unless two hands are used and care exercised in separating the keys, so that an important advantage of the type of key holder disclosed in said Murray 40 patent, i. e. the capacity for ready and convenient separation and manipulation of the keys by one hand, is largely lost. Not only does the wrapper thus tend to get in the way of the keys, but the separation from the group of the key which is adjacent the wrapper tends to exert a strain on the leather which tends to tear the wrapper away from the holder.

It is an object of this invention to provide a 45 construction of key holder and wrapper which largely avoids the difficulties heretofore experienced with the wrapper wrinkling and otherwise bunching up so as to interfere with the ready separation and manipulation of the keys.

Another object of this invention is to provide 50 a device of the type characterized which mini-

mizes the interference of the wrapper with one-hand operation of the group of keys.

Another object of this invention is to provide 5 a device of the type characterized which renders the inmost key as readily separable from the group as other keys therein, and without throwing any undue strains upon the material of the wrapper or tending to tear the wrapper from the group of keys.

Another object of this invention is to provide 10 a device of the type characterized which, while possessing the foregoing advantages, is also simple in construction, inexpensive to manufacture and easy to manipulate.

Other objects will appear as the description of 15 the invention proceeds.

The invention is capable of receiving a variety 20 of mechanical expressions, one of which is shown on the accompanying drawing, but it is to be expressly understood that the drawing is for the purpose of illustration only, and is not to be construed as a definition of the limits of the invention, reference being had to the appended 25 claim for that purpose.

Referring in detail to the drawing, wherein the 25 same reference characters are employed to designate corresponding parts in the several figures,

Fig. 1 is a perspective view of a key holder and wrapper of the present invention with the 30 wrapper in its closed position;

Fig. 2 is a similar view showing the opposite side of the package;

Fig. 3 is a perspective view of the wrapper 35 opened up, the keys removed, and the parts of the key holder proper separated for clearness of illustration; and

Fig. 4 shows the relative position of the parts, with keys in position, when the wrapper is open and a key is being manipulated by the right hand.

In the form shown the key holder proper may 40 be of any suitable construction, but is preferably of the general character shown and described in the aforesaid patent of Murray, No. 1,898,202.

As here illustrated it is composed of an internally threaded tubular shank 11 having an exterior surface hexagonal in cross section and provided with a head 12; a screw 13 having a head 14 and transverse slot 15; a tubular clamping member 16 having a head 17 and slidably mounted on said shank 11; and a spring lock 50 member 18 disposed between the heads 14 and 17. As the details of construction of said key holder constitute no part of the present invention, a further description of the construction and operation thereof is deemed unnecessary, but ref- 55

erence is made to the disclosure of said Murray patent.

In conformity with the present invention a key holder, as of the construction above referred to, is provided with a generally trapezoidal wrapper 20 of any suitable material, preferably leather. Said wrapper 20 may have the configuration illustrated on the drawing in Fig. 3, but is of such size and shape that it may be folded or wrapped about a group of keys equal to the maximum number of keys that the holder is adapted to retain and form a complete enclosure therefor, as shown in Fig. 1. Any suitable means may be provided for retaining the wrapper in its closed position, such as a snap, the two parts 21 and 22 of which are shown as suitably attached to the flap portions 23 and 24 of said wrapper. Disposed approximately midway of said wrapper is a stiffening member 25 which may be of any suitable shape and material, but is preferably formed of metal or some material having a relatively smooth surface for a purpose to be explained, and is of generally strip-like configuration. As shown the member 25 generally approximates the configuration of a key, but if preferred it may be made in the form of a plain strip, or may be made of any other suitable shape as preferred for reasons of design, advertisement, etc. Said member 25 may be attached to the wrapper in any suitable way, but is secured thereto at at least two points along the length thereof and adjacent the ends thereof, so that the wrapper is held taut and in flat surface contact with the member 25. As here shown the shank 11 of the key holder passes through a suitably shaped opening 26 adjacent one end of the member 25 and the wrapper 20 is clamped between the head 12 and said member, but the shank 11 may be made integral with the member 25, so that said member is in effect an extension of the shank 11, or the head 12 may be disposed between the member 25 and the wrapper, thereby providing more room on the shank for the keys. An eyelet or other suitable securing means 27 attaches the wrapper to the member 25 adjacent the opposite extremity of the latter and also, preferably, at at least one intermediate point, and if, as preferred, the head 12 does not extend to the exterior of the wrapper, a similar eyelet or other securing means attaches the wrapper to the member 25 adjacent the shank 11.

Said member 25 holds the wrapper taut and flat along its medial portion, and therefore the material of the wrapper cannot wrinkle or bunch up when a key is to be rotated with respect to the group of keys to move it into position for use. Moreover, the two ends of the wrapper become mere flaps by reason of the medial member 25, and as they are of flexible material they are easily deflected out of the path of a key as it is rotated, hence interposing a minimum interference to one-hand operation of the keys. Additionally, as the member 25 is of a material having a smooth face, the key adjacent thereto may be readily rotated into and out of the group without the frictional opposition to relative movement that would exist if the leather itself were in contact with the key, and to further facilitate relative rotation the member 25 may have a

slightly raised boss as shown at 28 in Fig. 3. The interposition of the member 25 prevents the transfer of stress to the wrapper when a key is moved with respect to the group, and therefore the rotation of the keys into and out of position is not productive of a tendency to tear or twist the wrapper away from its attachment.

When the wrapped group of keys is taken from the pocket, the parts are in the relative position shown in Fig. 1 with the snap holding the wrapper around the keys, whereby a compact and relatively regular and smooth package is afforded. With the thumb of the hand that is holding the article the snap can be readily released exposing the group of keys, and by manipulating the keys with the thumb of the hand they may be rotated relatively to the member 25 so as to select and further rotate the key to be used into the relative position shown in Fig. 4, all by the manipulation of one hand. During this manipulation there is little tendency for the wrapper to get in the way of the keys, and as the wrapper is in effect subdivided into two flexible flaps by the member 25 the manipulation of the keys easily deflects the flaps out of the way, and therefore there is a minimum interference with the selection and operation of the keys.

It will therefore be perceived that the present invention provides a key-holder with a wrapper for the keys which avoids all difficulties with the wrapper wrinkling and bunching up and interfering with the manipulation of the keys; which makes the innermost key as readily movable with respect to the group as the remaining keys; which eliminates the tendency to tear or twist the wrapper from the key holder; and which is strong and durable while at the same time simple and inexpensive to manufacture. While the embodiment of the invention illustrated on the drawing has been described with considerable particularity, it is to be expressly understood that the invention is not restricted thereto, as the same is capable of receiving other expressions as will now be apparent to those skilled in the art, while changes may be made in the details of construction, material, size, arrangement, and proportion of parts without departing from the spirit of this invention. Reference is therefore to be had to the appended claim for a definition of said invention.

What is claimed is:

In a key holder, a flexible wrapper, a stiffening member substantially traversing said wrapper and attached thereto adjacent its opposite ends to hold said wrapper taut dividing said wrapper into substantially equal parts, said stiffening member comprising a key-shaped metallic stamping of smooth surface with a non-circular aperture recessed in its outer and larger end to receive a key holding means and to prevent rotation of said key holding means, said key holding means extending at right angles to said stiffening member and retaining the keys in a generally aligned group and allowing rotation of said keys out of said generally aligned group and parallel to said stiffening member, and means locking the keys on said key holding means and allowing the addition or removal of keys.

ELDRIDGE R. FENIMORE JOHNSON.
